UNITED STATES PATENT OFFICE.

FRANK E. FISHER, OF DETROIT, MICHIGAN.

CASING FOR ENGINE-STARTER AND LIGHTING UNIT,

1,197,728.

Specification of Letters Patent. Patented Sept. 12, 1916.

Application filed November 5, 1914. Serial No. 870,365.

To all whom it may concern:

Be it known that I, FRANK E. FISHER, a citizen of the United States, residing at Detroit, county of Wayne, State of Michigan, have invented a certain new and useful Improvement in Casings for Engine-Starters and Lighting Units, and declare the following to be a full, clear, and exact description of the same, such as will enable others skilled in the art to which it pertains to make and use the same, reference being had to the accompanying drawings, which form a part of this specification.

My invention relates to an inclosing case for an electric motor and generator to adapt them for use as an engine starter and lighting unit.

One of the objects of the present invention is to construct an inclosing case or shell having an integral dividing wall forming separate chambers to respectively receive the armatures of the motor and generator in which the several pole pieces for the motor and generator are integral with the walls of the case.

Another feature of the invention consists in dividing the case by a vertical partition wall integral with the outer wall thereof to form a chamber entirely independent of the chambers in which the armatures are housed, to receive a train of gears and a clutch mechanism connecting the armature shafts of the motor with the armature shaft of the generator in turn directly coupled to the crank shaft of the engine (not shown), the object of the partition wall separating the gear case from the armature chambers being to insure against the passage of lubricant into the armature chambers from the gear case.

Other advantages and improvements will hereafter appear.

In the drawings accompanying this specification:—Figure 1, is a perspective view of the case with the end covers removed. Fig. 2, is an end elevation of the case with the plate covering the armature chambers removed. Fig. 3, is a longitudinal section on line 3—3 of Fig. 2. Fig. 4, is an elevation of the opposite end of the case showing the gear chamber,—the end plate being removed.

Referring now to the letters of reference placed upon the drawings: A, denotes a chambered casting provided with a vertical

partition wall B, integral with the outer walls of the casting.

B', indicates a horizontal partition integral with the outer wall of the casting and with the vertical partition forming a chamber C, for the armature of the motor D, (indicated by dotted lines in Fig. 2,) with a like chamber E, for the armature of the generator D',—also indicated by dotted lines in said figure.

C', C², C³, C⁴, are pole pieces for the motor formed integral with the walls of the casting.

E', E², E³, E⁴, are pole pieces for the generator, which are also integral with the walls of the casting.

F, F', are openings in the partition wall B, through which the shafts of the armature of the motor and generator project into a gear chamber G;—the openings being fitted with suitable gaskets f, f' to prevent the passage of lubricant from the gear chamber into the armature chambers of the casting.

G', denotes in dotted lines a train of gears housed in the chamber.

H, indicates a plate forming the end wall of the gear chamber provided with a projecting annular flange H' adapted to support a suitable bearing (not shown) for the armature shaft of the generator.

h, denotes a gasket encircling the shaft of the generator supported in a recess provided in the end plate H.

g is a gasket in the collar G² the upper part of the partition wall B, the collar being adapted to support a suitable ball bearing (not shown) for the armature shaft.

I, indicates a cover plate for the opposite end of the casting having an annular flange I', forming a chamber I², for the commutator and brushes of the motor and generator. The cover plate is also provided with recessed portions J, J', in alinement with the respective armature shafts of the motor and generator, to receive the supporting bearings (not shown) for the shafts.

Having indicated the several parts of the case by reference letters its construction and manner of housing the respective parts of the motor and generator will be readily understood. By casting the pole pieces integral with the walls of the case, I am enabled to materially reduce the cost of manufacture;—and by combining the motor and generator in a single unit, the necessary labor

and space required for installation is reduced to the minimum.

Having thus described my invention what I claim is:—

- 5 1. As a new article of manufacture, an inclosing case for an electric motor and generator comprising a chambered casting, an integral substantially horizontal wall dividing the casting into upper and lower chambers to receive the armature of a motor and generator, pole pieces for the motor formed integral with the walls of the casting, pole pieces for the generator formed integral with the walls of the casting, an integral substantially vertical wall dividing the casting to 10 form a gear chamber separate from the aforesaid chambers and provided with openings for the passage of the respective shafts of the motor and generator, a plate removable closing the outer side of the gear chamber, said removable plate having an inwardly directed recessed bearing disposed in alinement with the opening which establishes communication between the gear chamber and the generator chamber, and a removable plate to cover the outer sides of both the aforesaid upper and lower chambers.
- 20 2. As a new article of manufacture, an inclosing case for an electric motor and generator comprising a chambered casting, an

integral substantially horizontal wall dividing the casting into upper and lower chambers to receive the armatures of a motor and generator, pole pieces for the motor formed integral with the walls of the casting, pole pieces for the generator formed integral with the walls of the casting, an integral substantially vertical wall dividing the casting to 15 form a gear chamber separate from the aforesaid chambers and provided with openings for the passage of the respective shafts of the motor and generator, a plate removable closing the outer side of the gear chamber, said removable plate having an inwardly directed recessed bearing disposed in alinement with the opening which establishes communication between the gear chamber and the generator chamber, and a removable plate to cover the outer sides of 20 both the aforesaid upper and lower chambers, said latter removable plate having outwardly projecting upper and lower recessed portions forming bearings disposed opposite the motor and generator chambers, respectively.

In testimony whereof, I sign this specification in the presence of two witnesses.

FRANK E. FISHER.
